UNITED STATES PATENT OFFICE.

JEREMIAH SULLIVAN, JR., OF DUDLEY, PENNSYLVANIA.

DRILLING-MACHINE.

SPECIFICATION forming part of Letters Patent No. 527,462, dated October 16, 1894.

Application filed May 5, 1893. Serial No. 473,072. (No model.)

To all whom it may concern:

Be it known that I, JEREMIAH SULLIVAN, Jr., a citizen of the United States of America, residing at Dudley, in the county of Huntingdon and State of Pennsylvania, have invented 5 certain new and useful Improvements in Drilling-Machines, of which the following is a specification, reference being had therein to the accompanying drawings.

10 This invention relates to certain new and useful improvements in drilling machines having reference more especially to machines employed in quarrying and mining, and has for its object the provision of simple and efficient means for changing the feed for the 15 more effective operation on hard or soft material.

The invention comprises the details of construction, combination and arrangement of 20 parts, substantially as hereinafter fully set forth and particularly pointed out in the claims.

In the accompanying drawings:—Figure 1 is a view in side elevation. Fig. 2 is a plan view of the operative parts. Figs. 3, 4, and 25 5 are detail sectional views. Fig. 6 is a view of the two-part nut. Fig. 7 is a transverse sectional view on the line $x-x$, Fig. 2.

Referring to the drawings, A designates the 30 supporting frame consisting of side posts a united above and below by bridges a' which are secured to said side pieces in any suitable manner. From the lowermost bridge a' projects a spur a^3 while a threaded rod or bolt 35 a^4 works in a corresponding threaded sleeve a^5 of the upper bridge, said rod or bolt being pointed on its upper end and provided with a wheel a^6 . In practice the spur a^3 and pointed rod or bolt a^4 engage the floor and roof of the 40 drift, the same being adjusted to various heights by turning wheel a^6 .

B is the frame containing the operative portions of the machine, the projecting sides b of said frame fitting in recesses or cut-away 45 portions b' of side-bars a , whereby said frame may be positioned at various heights. A shaft C is journaled in bearings b^2 of frame B and on each end thereof is a crank handle b^3 . A large gear wheel b^4 is secured on one 50 end of shaft C inside the side bars b^5 of frame B and bearings b^2 while a smaller gear wheel b^6 is secured on the opposite end of said shaft,

said small gear wheel also being inside the side-bars b^5 . Both of these gear wheels are provided with sleeves b^7 extended through 55 bearings b^2 and gear-wheel b^5 is adjustably secured on the shaft C by a set-screw b^8 .

D is a gear wheel having an elongation d fitting in a sleeve d' of frame B said elongation having a flange d^2 so as to prevent lateral movement of said gear-wheel, which latter is provided with a longitudinal bore for the passage of the spindle d^3 . Said spindle is screw threaded and has longitudinal grooves d^4 in which fit spurs or projections d^5 of gear 65 wheel D whereby the spindle is rotated by the rotation of said gear-wheel.

E is a carriage mounted on frame B and the same is provided with flanges e designed to slide on the side bars of said frame. The 70 movement of the carriage is limited by a pin e' inserted in openings of frame B. In a sleeve e^2 of carriage E is designed to rotate the reduced portion of an elongation of a pinion e^3 in which is cut a groove e^4 to receive 75 the end of a screw e^5 which prevents lateral movement of said pinion independent of the carriage. A portion of the elongation of pinion e^3 adjacent to sleeve e^2 is cut out to form a hole or opening designed to receive a 80 pin e^6 , which is intended to prevent rotation of said pinion. The pinion e^3 is made hollow and the walls of said hollowed portion are provided with two grooves e^7 designed to receive ridges e^8 of a nut F. This nut is 85 formed in two parts f, f , hinged together at f' and provided with a female screw-thread f^2 .

The spindle d^3 is provided with a square socket f^3 for the reception of the squared end of bit f^4 which latter is provided with four 90 cutting edges f^5 by which means I am enabled to cut more rapidly and effectively.

In operation wheel b^4 meshes with the pinion D and gives it about three rotations to one; while gear b^6 meshes with pinion e^3 and 95 revolves the same in the direction of the motion of the spindle. It will thus be seen that these wheels and pinions being in engagement with each other the advance of the spindle d^3 is necessarily slow as the two-part 100 nut F is within the pinion e^3 and contains the thread for engaging the thread of the spindle which by this means is advanced in the direction of the feed, the said nut also

turning in the same direction as said pinion and spindle. In view of the foregoing the forward movement of the spindle will be one-third less than if pinion e^3 carrying the two-part nut was stationary. The method just described is the one used when the substance operated upon is hard and a slow feed is required.

To increase the speed I loosen the binding screw b^8 and move wheel b^6 to one side out of engagement with pinion e^6 , and insert pin e^6 in the opening in said pinion to prevent the latter from turning. In this way the advance or feed of the spindle will be increased one-third. It is obvious that by having a number of holes in side bars of frame B for insertion of pin e' , the carriage E may be moved to enable the use of a larger gear wheel than the one shown at b^6 , by the use of which the feed may be further varied.

From what has been said it will be seen that my invention is simple and durable and positive in its action. It will further be seen that the machine comprises but few parts and will not become easily deranged.

I claim as my invention—

1. A drilling machine comprising the supporting frame, the frame adjustably supported thereby, the gear-wheels and pinions mounted in said latter frame, one of said pinions being hollow and having grooves in its interior surface, a two-part nut having splines fitting in said grooves, the spindle in engagement with said two-part nut, the boring tool, means for imparting motion to said gear-wheels and pinions, and means, substantially as described, for holding said hollow pinion out of operation, whereby said spindle can be fed forward at an increased rate of speed, as set forth.

2. A drilling machine, comprising the supporting frame, the frame adjustably supported thereby, the gear-wheels and pinions mounted in said latter frame, the carriage also mounted in said latter frame, the hollow pinion mounted in said carriage and having interior grooves, the two-part nut having splines or feathers fitting in said grooves, the spindle in engagement with said two-part nut and operated by said gear-wheels and pinions, the boring tool, means for imparting motion to said gear-wheels and pinions, and means for holding said hollow pinion out of operation, the same comprising a gear-wheel with which said hollow pinion engages adjustably mounted on its bearing, said spindle being thereby capable of being fed forward at an increased rate of speed, substantially as set forth.

3. A drilling machine, comprising the supporting frame, the frame adjustably supported thereby, the gear-wheels mounted in the opposite sides of said latter frame, the hollow pinion mounted in one end of said latter frame, the carriage also mounted in said

frame and having a hollow pinion mounted therein, the two-part nut having splines or feathers fitting in grooves of said latter hollow pinion, the spindle in engagement with said two-part nut and the first mentioned hollow pinion, the boring tool, means for imparting motion to said gear-wheels and pinions, and means for holding the hollow pinion containing said two-part nut out of operation, the same comprising a gear-wheel with which said pinion engages adjustably mounted on its bearing, whereby said spindle is capable of being fed forward at an increased rate of speed, substantially as set forth. 75

4. In a drilling machine, the combination of the frame, the gear-wheels mounted in opposite sides thereof, the pinion mounted in one end of said frame, the carriage on the opposite end thereof having a hollow pinion mounted therein, the two-part nut having 80 splines or feathers fitting in grooves of said hollow pinion, the spindle in engagement therewith, means for imparting motion thereto, and means for holding said hollow pinion out of operation, the same comprising a gear-wheel with which said hollow pinion engages, adjustably mounted on its bearing, whereby said spindle is capable of being fed forward at an increased rate of speed, substantially as set forth. 90

5. A drilling machine, comprising the supporting frame, the frame adjustably supported thereby, the gear wheels mounted on opposite sides thereof, one of said gear-wheels being provided with a set-screw whereby the same may be adjusted to different positions, the pinion mounted in the end of said latter frame having a flange to prevent lateral movement, the carriage also mounted on said frame and having a pinion mounted therein, 95 the pin for preventing the rotation of the latter, the spindle in engagement with said pinions, the boring tool, and means for imparting motion to said gear-wheels and pinions, substantially as set forth. 100

6. An improvement in drilling machines, the frame, the frame supported thereby, the shaft mounted in said latter frame, the large gear wheel on one end of said shaft, the small gear wheel adjustably secured on the opposite end thereof, the hollow pinion mounted in the end of said frame meshing with the larger gear-wheel, the carriage also mounted on said latter frame, the hollow pinion mounted therein and meshing with said smaller gear-wheel having an elongation, the two part nut in said elongation, the spindle in engagement with said two part nut and also said former pinion, the boring tool, a pin designed to prevent rotation of said hollow pinion when out of engagement with said smaller gear-wheel and means for operating said gear-wheels and pinions, substantially as set forth. 115

7. In a drilling machine, the combination 120

of a hollow pinion having grooves in the inner surface, a two-part nut the sections of which are hinged together and interiorly screw-threaded, said sections being also provided with splines or feathers fitting in the grooves of said pinion, and the screw-threaded spindle in engagement with said two part nut, said nut being designed to re-

lolve with said hollow pinion, substantially as set forth. 10

In testimony whereof I affix my signature in presence of two witnesses.
